ELECTRIC IRON

Bernard H. Pickard and Lawrie G. McIntosh, Toronto,
Ontario, Canada, assignors to Steam Electric Products
Limited, Toronto, Ontario, Canada

Application October 28, 1953, Serial No. 27,369

Term of patent 7 years

(Cl. D49—6)

To all whom it may concern:

Be it known that we, **Bernard H. Pickard and Lawrie G. McIntosh**, citizens of Canada, residing at Toronto, Province of Ontario, Canada, have invented a new, original, and ornamental Design for an Electric Iron, of which the following is a specification, reference being had to the accompanying drawing, forming a part thereof.

Fig. 1 is a perspective view of an electric iron, showing our new design;

Fig. 2 is a perspective view, thereof taken from the opposite side; and

Fig. 3 is a bottom plan view thereof.

We claim:

The ornamental design for an electric iron, as shown.
